CLOSURE OPERATING DEVICE

John Slatinsky, Chicago, Ill.

Application February 25, 1936, Serial No. 65,691
Renewed June 1, 1937

1 Claim. (Cl. 189—69)

This invention relates to the broad class of closure operating means and structures and it has more specific reference to a manually controlled mechanical device which is especially, but not necessarily adapted for opening and closing vertically swingable hingedly mounted windows or equivalent closures.

Briefly, the preferred embodiment of the invention has to do with a novel structural assemblage which includes among other parts a pair of end plates rigidly attachable to the window frame and constructed to serve as special adaptors as well as stops for limiting the outward swinging movement of the window when it is swung to its open position.

The principal novelty, however, resides in the adoption and use of a special hand crank operated lever, actuating means therefor, and an operating connection between the lever and the frame of the window or sash, whereby to positively open and close the window in accordance with the movement of the hand crank and its associated lever.

In carrying the invention into actual practice, I have carefully selected and mechanically coordinated the aforesaid and other incidental features to provide a structural assemblage of a comparatively simple and efficient nature which, it is believed can be aptly fitted for the purposes intended and while susceptible of affording the trade and those interested with a satisfactory invention and one which is practicable and otherwise well designed and equipped to perform the desired results with requisite certainty.

Other features and advantages of the invention will become more readily apparent from the following description and the accompanying illustrative pictorial drawings.

In the drawings:

Fig. 1 is a view which may be designated as an inside elevational view, showing the attachment constituting the invention and disclosing the window in closed position.

Fig. 2 is a fragmentary vertical sectional view on a slightly enlarged scale, the section being taken approximately on the plane of the line 2—2 of Fig. 1.

Fig. 3 is a detail view partly in section and elevation disclosing the gearing, gear housing, lever and allied parts of the assemblage.

Fig. 4 is a perspective disclosing the permanently anchored keeper channel forming an essential part of the structure.

In the drawings, Fig. 1 for example the sta-

tionary window frame is denoted by the numeral 5 and the swingable sash or window indicated at 6. This is hingedly attached to the sill structure as denoted at 7 and is designed to swing inwardly to an inclined position for room ventilating purposes. Rigidly attached to the window frame at points just above the sill I provide a pair of substantially duplicate adapter or end plates 8 and 9. Each plate is substantially triangular in end elevational view and is provided with an outstanding attaching flange 10 rigidly secured to the window frame, while at the outer end is an inturned stop flange 11. One of the frame members of the window sash (as shown in Fig. 4) and denoted by the numeral 12 is a recess or mortise and fixed into this is a channel-shaped part 13 which may be conveniently referred to as the keeper as well as a wear and actuating member. Cooperable with this keeper 13 is a laterally directed stud or pin 14 rigidly mounted on the outer end of the operating lever 15. Various means may be employed to operate this lever but I prefer to utilize a device which may be attached to the outside of the web or body portion of end plate 9. The attachment comprises a casing or gear housing 16 in the form of a simple rectangular casing. This is secured by suitable fasteners as at 17 for cooperation with an arcuate slot 18 formed in said plate. The slot serves to accommodate the offset portion 19 of the lever. The inner end of the lever is secured to a stub shaft 20 mounted in the casing and carrying the main operating gear 21.

For the purpose of turning the gear 21 I utilize a train of gearing which includes a large pinion 22 mounted on the crank shaft 23. In addition to carrying the gear 22 the shaft 23 also carries a suitably located hand crank 25 and a smaller pinion 26 which is in mesh with the teeth of the gear 21. I also utilize additional gears 27 and 28, these being confined in the gear housing and meshing with the two gears or pinions 22 and 26 respectively.

It is evident that with this arrangement by rotating the shaft 23 through the instrumentality of the hand crank 25, this operates the pinions 22 and 26. Such action also rotates the gear 21 to actuate the lever 15. The lever 15 being operatively connected with the window through the instrumentality of the pin 14 and the associated channel 13 obviously serves to swing the sash inwardly to open position. The reverse is true when the crank 25 is turned in the opposite direction. Hence it is evident that the attach-

ment constitutes a satisfactory and reliable means for opening and closing the hingedly mounted window sash or equivalent closure.

- It is thought that persons skilled in the art to which the invention relates will be able to obtain a clear understanding of the invention after considering the description in connection with the drawings. Therefore, a more lengthy description is regarded as unnecessary.
- 5 Minor changes in shape, size, and rearrangement of details coming within the field of invention claimed may be resorted to in actual practice, if desired.
- 10

I claim:

An attachment of the class described comprising a substantially triangular plate formed at one end with an attaching flange for attaching to a window frame and at its opposite end with a stop flange, said plate being further provided with an arcuate slot, a lever having an intermediate offset portion operable in said slot, one end of said lever being provided with an operating device for connection with a hinged closure, a gear connected to the other end of said lever and a hand crank for operating said gear.

JOHN SLATINSKY.
